(57) **CLAIM**

We claim the ornamental design for the speaker enclosure, as shown and described.

DESCRIPTION

FIG. 1 is a front, left side perspective view of the speaker enclosure of our new design;

FIG. 2 is a front view thereof;

FIG. 3 is a rear view thereof;

FIG. 4 is a left side view thereof, the right side being a mirror image; and,

FIG. 5 is a top view thereof, the bottom view being a mirror image.

The broken line showing on the drawing disclosure is for illustrative purposes only and forms no part of the claimed design.
